2 SHEETS—SHEET 2.

Inventor:

James Tallon

By *Detznerup*
Attorney.

UNITED STATES PATENT OFFICE.

JAMES TALLON, OF LONG BEACH, CALIFORNIA.

PLACER-MINING MACHINE.

Application filed January 4, 1922. Serial No. 526,917.

To all whom it may concern:

Be it known that I, JAMES TALLON, a citizen of the United States, residing in the city of Long Beach, county of Los Angeles, State of California, have invented certain new and useful Improvements in Placer-Mining Machines, of which the following is a specification.

My invention relates more particularly to a machine adapted to be used in the desert, and in other places where what is known as dry placer mining is or can be conducted. It is adapted to be transported from place to place, and to be hand operated, although, of course, power can be used for operating the same where available.

In order to explain my invention I have illustrated the same on the accompanying two sheets of drawings, in which,—

20 Figure 1 is a top plan view of a machine embodying my invention;

Figure 2 is a side elevation thereof;

Figure 3 is a fragmentary sectional view taken on the line 3—3 of Fig. 1; and

25 Figure 4 is a similar view taken on the line 4—4 of Fig. 1.

Referring now more in detail to the drawings, my invention, as here shown for illustrative purposes, comprises a general 30 frame composed of four corner posts 1, 1, connected at their upper ends with cross beams 2, 2, at the side, and 3, 3, at the front and rear, said frame preferably being mounted on runner members 4, 4. Pivotally 35 supported from the top of said frame by eye-bolts 5—5, and links 6, 6, in an inclined position, is a swinging box or bed 7, as clearly seen in Fig. 4. Mounted in said box or bed are two riffle pans, 8 and 9, with the 40 riffles 10, 10, therein as will be clear from Fig. 4. The riffle pan 8, is mounted rearwardly of and above the riffle pan 9, and in such relationship thereto that overflow therefrom will be discharged into the riffle pan 9. It will be seen that the riffles are 45 arranged crosswise of the pans so that matter passing from one pan to the other must pass over the riffles. Above the riffle pan 8, in an inclined position, is mounted a screen 50 11, around three sides of which is a wall or flange 12. It will be seen that the box or bed 7, is wider than said riffle pans 8 and 9, providing at one side a runway 13. Said screen preferably tilts slightly toward said 55 runway and that side thereof is open so that coarse gravel discharged onto said screen

will be discharged into the runway, and be moved downwardly, because of the incline of said box or bed, to the guide walls 14, 14, and thus be discharged at the lower side of 60 the machine onto a conveyer belt 15, hereinafter again referred to. Mounted above the riffle pan 9, are hinged doors 16, 17, which may be closed down and locked, as by means of a padlock 18, Fig. 1. Said 65 riffle pans are removable from the bed or box 7, and in the construction shown, the upper riffle pan must be removed first out over the lower riffle pan. When said doors 16, 17, are locked said riffle pans are inaccessible and cannot be removed. Said riffle pans will be supplied between the riffles with a quantity of quicksilver. The gravel and sand containing the gold will be shovelled onto an endless conveyer belt 19, supported in a frame 20, having rollers 21, and the drive shaft 22, with pulley 23. A main drive shaft 24, is mounted in said frame and is provided with a driving pulley 25, connected by means of a belt 26, with the pulley 23, for driving said endless belt 19. On the outer end of said main drive shaft 24, is a large driving pulley 27, provided with a handle 28, for hand operation. A second drive shaft 29, is mounted in the forward 85 part of said frame and is provided on its outer end with a pulley 30, over which runs a belt 31, from the large pulley 27. Said shaft 29, is also provided with a smaller pulley 32, over which runs a belt 33, to a 90 pulley 34, on a shaft 35, at the lower end of the frame 36, upon which is supported and driven the endless belt 15, similar to the belt 19. These supporting frames 20 and 36, on which are the belts 19 and 15, are adjustably 95 mounted in any suitable manner, and may be supported by an adjustable leg or frame as 37, Fig. 2. Mounted on the shaft 29, is a beveled gear 38, which meshes with another beveled gear 39, mounted on a crank shaft 100 40, supported in suitable bearings 41, 41, on the frame members 42, 42. Said crank shaft 40, is pivotally connected by means of a pitman arm 43, with the bed or box 7, as at 44, whereby when said crank shaft 40, is 105 operated, said body or box will be given an oscillating movement longitudinally of the riffles, but crosswise of the main frame.

The use and operation of my invention may be briefly described as follows: Assuming that the machine has been moved on to a location where there is sand and gravel

containing gold, the sand and gravel is shoveled on to the conveyer belt 19, while the machine is in operation from which it is discharged on to the inclined screen 11, 5 above the riffle pan 8, the coarse gravel will be jostled off the lower side of the screen 11, into the runway 13, while the finer gravel and sand will pass through the screen 11, and into the quicksilver in the riffle pan 10 8. As said pan 8, is filled up between the riffles, the overflow will run into the lower pan 9. It will be understood that during this operation the body or box is being oscillated in the manner referred to which 15 agitates the quicksilver longitudinally between the riffles and causes it to move back and forth under the sand and gravel thereon in a way to agitate and shift the sand and gravel so that any gold or precious 20 metal which may be mixed with the sand or gravel will be gathered by the quicksilver. This quick oscillating movement of the bed or box not only agitates and settles the sand and gravel, but also agitates the 25 quicksilver in its confined spaces between the riffles thereby making more effective its function of gathering the gold from the sand and gravel discharged thereonto. This agitation also causes the gold to settle into 30 the quicksilver. It will be understood of course that the coarser gravel and sand will overflow from one riffle to the other and finally be discharged on to the discharge belt 15, by which it is carried away from 35 the machine. It will be apparent from the construction, that the riffle pans can be easily removed at any time and the amalgam cleaned in the usual manner.

I am aware that my invention can be embodied in many different forms and in which the riffle pans will be supported for oscillation, and I do not therefore limit my

invention to the details here shown for illustrative purposes, except as I may be limited by the hereto appended claim. 45

I claim:

A placer mining machine comprising in combination, a supporting structure adapted to be moved from place to place, a bed suspended in said structure, in an inclined position, and adapted to be swung transversely of said structure, a riffle pan with spaced riffles therein arranged transversely of said structure, said pan being mounted in the upper side of said bed and at one 55 side thereof, to leave a space at the side of the bed, a screen over said riffle pan, a wall around three sides of said screen, the side next to the space in said bed being left open, a second riffle pan mounted in the bottom of said bed, below said first pan, with riffles therein, said second riffle pan being below the bottom of said first pan and adapted to receive overflow therefrom, a 60 cover over said second pan, said bed being open at its lower side whereby overflow from said riffle pans is discharged therefrom, the space at the side of said bed also being open to the discharge lower side thereof, with means for guiding matter from 65 said space to the discharge side of said bed, means for swinging said bed and said riffle pans together longitudinally of said riffles, and means for feeding sand and gravel to the screen above the first riffle pan, 70 substantially as shown and described. 75

Signed at Los Angeles, Los Angeles County, California, this 23rd day of December, 1921.

JAMES TALLON.
